RECIPROCATING ENGINE WITH START-RUN
CONDITIONING MEANS

Willem Jan van Heeckeren, Eindhoven, Netherlands, assignor to Hartford National Bank & Trust Co., Hartford, Conn., as trustee

Application September 7, 1945, Serial No. 615,048
In the Netherlands November 9, 1943Section 1, Public Law 690, August 8, 1946
Patent expires November 9, 1963

12 Claims. (Cl. 74—573)

1

The present invention relates to an off-dead-center piston positioning mechanism for piston type engines, and more particularly to "start-run" conditioning apparatus for hot gas engines; and, specifically, to a distinct two state mechanical energy storage mechanism.

For starting a hot gas engine use may be made of a separate power source, in the form of a hand drive, an auxiliary motor or compressed air. These means are used very often for explosive and combustion type motors. It has already been proposed to start a hot gas engine by the gaseous pressure in one or more cylinders after the supply of heat has been turned on, and this pressure according to the thermodynamic cycle process to be traversed must exist in the cylinder in question at a momentary position of the working piston conducive to the transmitting of torsional moments upon a crank shaft.

In the latter case as well as with starting by means of compressed air, for instance, the possibility of starting the engine depends, however, on at least one of the pistons occupying a position advantageous for starting. In the case of engines having three or more cylinders whose cranks are at an angle with one another which in the case of two-cylinder motors have their cranks about an angle of 90° to each other, one of the working pistons practically always occupies an advantageous position. However, if one of the mentioned pistons is not in an advantageous position it must be brought into such a position before starting of the engine can be initiated.

Therefore, a principal object of the invention is to provide means to overcome the above problem.

Another object of the invention is to provide start-run conditioning apparatus for hot gas engines.

A further object of the invention is to provide an off-dead-center engine positioning device.

Other objects and advantages of this invention will be apparent from the description of the invention set forth hereinafter.

Fig. 1 shows a diagrammatic view in elevation of one embodiment of this invention.

Fig. 2 shows a similar view of another embodiment of the invention omitting the engine mechanism; and

Fig. 3 shows a variation of the Fig. 2 embodiment.

Generally speaking this invention proposes to add to and combine with the piston and allied

2

parts of an engine such as a hot gas engine, an eccentric mass so oriented with the energy transfer elements therein such as piston means that the energy stored in this mass during engine operation will always carry the piston means to the proper position for engine starting from an inactive state of the same and to further combine a movable weight with this mass in such an arrangement that the eccentric mass is balanced at a predetermined minimum speed of engine rotation associated with the lower limit of normal engine speeds. Stated more succinctly the invention contemplates a combined engine start-conditioning mechanism and engine run-conditioning mechanism including a combined eccentric mass and movable mass in one position with allied parts forming an embodiment for the first phase, the engine "start-conditioning part" of the inventive concept, and the eccentric mass with the movable weight in a second centrifugally generated position with allied parts forming the second phase, the engine "run-conditioning part" of the inventive concept.

According to the invention, the new hot gas engine combination includes a crank shaft which at one side is made heavy in such a manner that when the motor comes to rest, a position is reached where at least one of the movable surfaces in the motor cylinders coupled to the crank shaft is subjected to the action of the variation in pressure resulting from a cyclic thermal process thereby producing the desired direction of rotation of the engine and enlarging the space in which the thermodynamic cycle is performed. The above constitutes the first phase of the inventive concept.

When such an engine is at rest the increase of the gaseous pressure in the space in which the cyclic process is performed, as a rule the cylinder of the motor, will result in such a movement of the movable surfaces that the volume of this space is increased. Thus, the crank shaft is set into motion and the engine is started. This increase in pressure may be effected either by introducing a gas under pressure at regular intervals or by a single introduction of a quantity of gas, whereafter the thermodynamic cycle begins.

The heavy side of the crank shaft displaces the center of gravity of the crank shaft, together with the crank, the driving rod and the counterweights to outside the axis of revolution. With a slow-running motor this need not necessarily be objectionable. For fast-running motors, however, it is advisable not to continue this position during operation in order to prevent the occur-

rence of troublesome vibrations. According to the invention in this case the center of gravity above a definite speed of the crank shaft is brought into or as well as possible into the axis of revolution preferably by the arrangement of a separate mass capable of being displaced under the action of centrifugal force. This constitutes a second phase of the inventive concept.

In order that the invention may be clearly understood and readily carried into effect, it will be described more fully by reference to the accompanying drawing.

In Fig. 1, showing an off-dead-center engine conditioning mechanism, reference numeral 10 denotes the cylinder of a hot-gas motor in which the piston 12 and the displacer 11 move up and down. This cylinder 10 is surrounded by a heater 13, a regenerator 14 and a cooler 15. The drive for the displacer 11 is not shown further since the drive is not essential to an understanding of the present invention. The piston 12 is coupled in the usual manner to the crank 18 on the crank shaft 19 with the aid of a piston rod 16 and a driving rod 17. For starting such a motor without utilizing hand drive or a separate auxiliary motor it is necessary that the piston 12 in the desired direction of rotation has just passed the upper dead position, or in other words that it is in the beginning of the expansion stroke. This advantageous position may be attained by stopping the motor in this position at the end of a working period with the aid of a weight secured to one side of the crank shaft 19. This separate weight 24 is secured to the crank shaft with respect to the crank or the cranks in such a manner that, when this weight occupies the lowest position under the action of gravity, at least one of the pistons is in the beginning of the expansion stroke. However, since in normal operation all the rotary parts of the machine must be balanced this separate weight must be removed again or made up for as soon as the motor is started. The separate weight 24 is secured to the heavy wheel or flywheel 20 of the motor. Diametrically opposite thereto is arranged a second weight 21 which is pivoted in 22 on the said flywheel 20. These two weights or masses 21 and 24 are so arranged and of such masses that in the position of the weight 21 which is radially directed to the circumference of the flywheel the common center of gravity of the two weights lies exactly in the center of the crank shaft 19 after the engine attains a predetermined speed. Since with a rotating flywheel the weight 21 will occupy the above-mentioned position of its own accord under the action of centrifugal force, the balancing of the crank shaft together with the associated parts is not disturbed by this weight when the motor is rotating. The movable weight 21 has, however, fastened to it a spring 23 which tends to move this weight toward the center line of the crank shaft 19 against the action of the centrifugal force. Below a definite rotational speed of the crank shaft 19 the force of this spring or confining means 23 will exceed the centrifugal force so that the weight 21 moves to or toward the center line of the crank shaft. The distance between the point of attachment of the spring 23 on the weight 21 and the journal 22 is made as small as is possible for reasons of constructional nature, in order practically to eliminate the weight action of the resilient means 23 upon the position of the weight 21 when the definite speed is exceeded. The common point of gravity

of the two weights when unaffected by rotation thereof is displaced in the direction of the weight 24 so that the motor will at last be at rest with the weight 24 approximately in its lowest position. This corresponds to such a position of the crank that at least the piston 12 is in a position advantageous for starting.

The weight 21 which can turn about the journal or pivot means 22 serves not only for the above-described object but also as a damping member for the torsional vibrations which occur in the crank shaft due to the variable tangential force on the crank 18.

Fig. 2 shows another form of construction of a "start run" engine conditioning device in which for stopping in a definite position when the motor is rotating above a definite speed, a weight 25 is balanced by a slidably counterweight or mass 26. The heavy wheel 20 itself has provided on it two guides or confining means 27 between which the weight 26 can move radially. In the position of rest and at low speeds a spring or confining means 28 which fits a cylindrical cavity 29 of the weight 26 forces this weight towards the hub of the heavy wheel 20. Above a definite engine speed the centrifugal force surpasses the resilient pressure of the spring 28 and in this case the weight 29 is pressed or confined against the outer edge of the fly wheel, thus exactly balancing the weight 25.

Fig. 3 shows a fly wheel 20 which, as is usual with comparatively heavy flywheels, is constituted of two parts. Two cavities or reservoirs 30 and 31 are recessed diametrically opposite each other in the casting. Furthermore, inside the rim of this fly wheel lies a closed tube or concentric channel 32 which by means of a short connecting piece 33 is in open communication with one of the recessed cavities 31. The tube or connective channel 32 and the cavity 31 are jointly filled with an amount of liquid approximately sufficient to fill the cavity 31. A cavity 30 opposite cavity 31 is filled up with a block of solid material whose weight is equal to that of the amount of liquid filling the cavity 31. When the heavy wheel 20 is rotating the cavity 31 is filled with liquid due to centrifugal force, so that the weight of the filling material of the cavity 30 is balanced. When the speed of the fly wheel decreases the liquid is distributed over the tube 32 so that the filled-up cavity 30 constitutes the heaviest point of the fly wheel.

What I claim is:

1. In a reciprocating engine a positioning device comprising a piston, connecting rod means therefor, crank shaft means coupled to the free end of said means, a heavy wheel attached to said shaft means, an eccentrically located first fixed mass on said wheel, said first fixed mass being located on said wheel so that when said wheel is permitted to stop rotating, said wheel finally attains a position of rest due to said first fixed mass which causes said piston, through the mechanical linkage of said crankshaft and said connecting rod means, to assume a position favorable for re-starting said engine, a second separate movable mass normally unbalanced with said first mass and confining means on said wheel for said movable mass, said mass moving into a position of equilibrium with respect to said first mass under a predetermined centrifugal force and moving out of said position of equilibrium when said predetermined centrifugal force is not attained.

2. In a reciprocating engine a positioning de-

vice comprising a piston, connecting rod means therefor, crank shaft means coupled to the free end of said means, a heavy wheel attached to said shaft means, a weight means disposed from the center of said wheel, said weight means being located on said wheel so that when said wheel is permitted to stop rotating, said wheel finally attains a position of rest due to said weight means which causes said piston, through the mechanical linkage of said crankshaft and said connecting rod means, to assume a position favorable for re-starting said engine, a movable mass forming a part of said wheel, said mass taking up a position directly opposite said weight means and in balance therewith upon said wheel attaining a predetermined minimum rotational speed and means for returning said mass to an off-balanced location relative to said weight means at a wheel speed below said minimum speed.

3. In a reciprocating engine as claimed in claim 2 wherein said movable mass is pivotally coupled to said wheel.

4. In a reciprocating engine as claimed in claim 2 wherein said movable mass is slidably coupled to said wheel.

5. A two state mechanical energy storage device comprising a heavy wheel, a fixed weight eccentrically disposed on said wheel, pivot means positioned diametrically opposite the center of said weight, a second like weight on said pivot means, and resilient means attached to said second weight and said wheel yieldable under a predetermined centrifugal action applied to said second weight at a predetermined wheel speed whereby said weights are balanced.

6. A start-run engine conditioning device comprising a heavy wheel, an eccentrically located weight attached thereto, a separate movable mass normally unbalanced with said weight and confining means for said mass on said wheel, said mass taking up a position with respect to said weight to counterbalance said weight at a predetermined centrifugal force imparted to said mass by the speed of rotation of said wheel caused by the running engine, said confining means including a reservoir joined by a connective channel.

7. In combination an engine and a conditioning device therefor comprising piston means, crank means connected to said piston and including a shaft, a heavy symmetrical mass surrounding said shaft, a first eccentric weight means on said symmetrical mass oriented with said piston means, so that upon rotational stoppage of said shaft and said symmetrical mass surrounding said shaft, said eccentric weight means causes said symmetrical mass and said shaft to assume a position which in turn through said crank means assures that said piston stops in a position favorable for re-starting said engine, a reservoir located diametrically opposite said eccentric weight means, a concentric channel joined to said reservoir, a movable mass substantially equal to said eccentric means normally confined within said channel, said movable mass assuming a position within said reservoir at the time a predetermined engine speed is attained, whereby a balanced engine condition is produced and assuming a position within said concentric channel at the time a predetermined engine speed is not attained whereby an unbalanced engine condition is produced.

8. In a reciprocating engine a positioning device comprising a piston, connecting rod means

therefor, crank shaft means coupled to the free end of said means, a heavy wheel attached to said shaft means, an eccentrically located first mass on said wheel oriented with said piston, so that upon rotational stoppage of said shaft and said heavy wheel, said eccentrically located first mass causes said wheel and said draft to assume a position which in turn through said crankshaft means assures that said piston stops in a position favorable for re-starting said engine, guide means having a longitudinal axis on a wheel diameter containing the center of gravity of said first mass, a movable second mass confined in said guide means, and resilient means within said guide means for forcing said second mass toward said first mass under all engine speeds below a predetermined normal, said guide means including a outer stop for said second mass, whereby a centrifugal force corresponding to a normal engine speed forces said second mass into balance with said first mass.

9. A reciprocating engine comprising a piston, a crankshaft, means connecting said piston to said crankshaft, a weight attached to said shaft in eccentric relationship thereto, the position of said weight being such that upon stoppage of said engine, said weight causes said crankshaft to turn to a position which in turn through said connecting means causes said piston to stop in a position of rest favorable for restarting, and a mass movably connected to said shaft and arranged to move to a location to counterbalance said eccentrically attached weight as soon as a predetermined speed of rotation of said crankshaft is reached.

10. A reciprocating engine according to claim 9 wherein said mass is hingedly mounted on a pivot connected to said crankshaft, and a spring attached to said mass and to attachment means connected to said crankshaft and arranged to bias said mass to an unbalancing location with respect to said weight when the speed of rotation of said crankshaft falls below said predetermined speed.

11. A reciprocating engine according to claim 9 wherein said mass is slidably coupled to said shaft.

12. A reciprocating engine according to claim 9, wherein there is a flywheel on said shaft, said flywheel having a concentric annular channel adapted to have a liquid mass therein and communicating with a widened cavity situated diametrically opposite said eccentrically located weight, said widened cavity being at a greater distance from the axis of said flywheel than said annular channel, whereby the liquid mass may flow to said cavity due to centrifugal force when said flywheel attains a predetermined speed of rotation.
